CLAIM

The ornamental design for a cover of an electronic device with surface pattern, as shown and described.

DESCRIPTION

FIG. 1 is a perspective view of a cover of an electronic device with surface pattern showing our new design;

FIG. 2 is a front elevational view thereof; and,

FIG. 3 is a side elevational view thereof.

In the drawings, the broken lines indicate portions of the cover of an electronic device with surface pattern that form no part of the claimed design.
